[57] CLAIM

The ornamental design for a hand held sprayer, as shown and described.

DESCRIPTION

FIG. 1 is a perspective view of a hand held sprayer showing my new design;

FIG. 2 is a side elevational view thereof, the opposite side being a mirror image;

FIG. 3 is a front elevational view thereof;

FIG. 4 is a rear elevational view thereof;

FIG. 5 is a top plan view thereof;

FIG. 6 is a bottom plan view thereof;

FIG. 7 is a fragmentary cross-sectional view thereof, taken along 7—7 of FIG. 2;

FIG. 8 is a fragmentary cross-sectional view thereof, taken along 8—8 of FIG. 2;

FIG. 9 is a fragmentary cross-sectional view thereof, taken along 9—9 of FIG. 2;

FIG. 10 is a fragmentary cross-sectional view thereof, taken along 10—10 of FIG. 2;

FIG. 11 is a fragmentary cross-sectional view thereof along 11—11 of FIG. 2; and,

FIG. 12 is a cross-sectional view thereof, taken along 12—12 of FIG. 2.
